CONVERSION OF HYDROCARBON GASES
INTO LIQUID HYDROCARBONSCary E. Wagner, Chicago, Ill., assignor to The
Pure Oil Company, Chicago, Ill., a corporation
of Ohio

Application June 17, 1936, Serial No. 85,711

11 Claims. (Cl. 196—10)

This invention relates to the conversion of gaseous hydrocarbons into liquids and is more particularly concerned with the conversion of olefinic hydrocarbon gases into aromatic liquid hydrocarbons.

It is well known that hydrocarbons of the methane series can be converted into aromatic hydrocarbons by heating to above 1200° F. and preferably above 1400° F. at atmospheric pressure or at super-atmospheric pressures up to 200 pounds per square inch. It is also known that olefin-containing gases can be converted into hydrocarbons boiling within the gasoline range by heating to temperatures of approximately 15 700°—1050° F. under high super-atmospheric pressure. However, the polymers resulting from the latter process are predominantly of the olefinic or naphthenic type.

The object of this invention is to convert olefinic gases into aromatic hydrocarbons.

Another object of the invention is to provide a process of converting straight chain hydrocarbons into aromatics at much lower temperatures than have been used heretofore.

25 A further object of the invention is to provide a low pressure method of polymerizing olefin containing gases.

Still another object of the invention is to provide a process capable of producing high yields 30 of toluol.

A still further object of the invention is to produce a novel product which may be fractionated into useful components or may be used as a motor fuel.

35 In accordance with the invention, olefin-containing gases in which the concentration of olefins is held within certain limits, preferably 40-60% by weight, are heated to a temperature of from 1100°—1200° F. for a period of time ranging 40 from 5 to 30 seconds and then quickly chilled to a temperature below reaction temperature. The condensate resulting from the process has an unusually high toluol content. This condensate is not only extremely valuable for the individual 45 compounds that may be fractionated therefrom, but is also valuable as a motor fuel because of its high octane number.

In order to more clearly understand the invention, reference should be had to the following description and the accompanying drawings, 50 of which,

Fig. 1 is a diagrammatic elevational view of apparatus suitable for carrying out the invention, and

55 Fig. 2 is a graph showing the distillation range

of the product made in accordance with the process.

Referring to Fig. 1, wet gas from a vapor phase or other cracking unit is charged through line 1 by means of compressor 3, which compresses the 5 gases to approximately 150-300 pounds per square inch, preferably about 175 pounds per square inch, and then passes cooling coil 5 into accumulator 7. The gases in passing through cooling coil 5 are cooled down to substantially 10 atmospheric temperature and any liquids which condense are discharged from the accumulator 7 through the line 9 into the mix tank 11. The uncondensed gases leave the top of the accumulator 7 through the line 13. These gases will contain from 40-55% of unsaturated hydrocarbons (olefins) if they result from a vapor phase cracking operation, or a lesser percentage of olefins if the gases have been produced in a high pressure cracking operation. The gases may come 15 from any other desirable source, as for example, from a gas cracking operation. From the line 13 the gases pass into the lower portion of the absorber 15 wherein they are contacted with a counter-current stream of absorber oil such as 20 mineral seal or light gas oil, which is fed into the upper portion of the absorber through the line 17. The pressure in the absorber may be maintained at approximately 150-200 pounds per square inch and preferably about 165 pounds 25 per square inch. At this pressure the heavier gases such as propane, propylene, butane, and butylene, as well as any heavier fractions which may still be present in the gases, together with some ethane and ethylene, are absorbed by the 30 absorber oil. The remaining unabsorbed gases, which will comprise hydrogen, methane, ethane, ethylene, and possibly some propane and propylene, will be discharged from the top of the absorber through the line 19. These gases may 35 be either eliminated from the system through the line 21 controlled by back pressure regulator 23, or may be charged through the line 25 controlled by valve 27, to be mixed with other gases before charging to the polymerization system. 40 It will be evident that the gases leaving the top of the absorber may be split and part withdrawn from the system and part fed to the polymerization unit.

The rich oil is withdrawn from the lower part 50 of the absorber through the line 31 controlled by valve 33 and passes into a fixed gas eliminator 35 where the pressure is maintained at approximately 100 pounds per square inch. A small portion of the gas, comprising the lighter con- 55

stituents dissolved in the absorber liquid, escape from the top of the fixed gas eliminator through the line 37 controlled by valve 39. This gas may be withdrawn from the system and used for any desired purpose, as for example, for fuel, or may be charged to the polymerization system. The rich oil is then withdrawn from the fixed gas eliminator through the line 41 by means of pump 43 and passes through heat exchanger 45 and preheater 47 into the upper portion of the still 49. The rich oil in the still 49 is circulated through line 51, reboiler 53 and line 55 in indirect heat interchange with hot oil which is circulated from a suitable heater (not shown) through the line 57, reboiler 53, line 59, preheater 47, and back to the heater through line 61. The hot oil passes in indirect heat interchange with the rich oil in the preheater 47 before being returned to the heater.

In the still 49 the rich oil is denuded of its absorbed gas and light gasoline fraction, which leave the top of the still through the line 63. From the line 63 the gases and light gasoline fractions pass through the condenser 65 into the separator 69 from which water and condensed gasoline fractions are withdrawn through lines 71 and 73 respectively. The water present in the condensate is due to the open steam which may be charged into the still 49 through the line 75 to assist in stripping the absorbed gas and gasoline line fraction from the absorber oil. The denuded oil is returned by means of pump 76' through line 76, heat exchanger 45, cooling coil 78 and line 17 to the top of the absorber 15. The still 49 and separator 69 may be operated at a pressure of approximately 100 pounds per square inch. From the separator the condensed hydrocarbons pass through the line 73 and line 17 into the mix tank 11. The uncondensed gases, composed chiefly of ethane, ethylene, propane and propylene, leave the top of the separator 69 through the line 79 controlled by valve 81 and may be discharged from the system through line 83 controlled by valve 85, or may be united, in whole or part, with the fresh gases charged to the system through the line 1. A small amount of gas may be liberated in the mix tank 11 and this gas leaves the top of the tank through the line 87 and joins the gases leaving the top of separator 69 through the line 79.

Condensate is withdrawn from the mix tank 11 through the line 89 by means of pump 91 and a portion thereof may be charged into the top of the still 49 through the line 93 as reflux. The major portion of the condensate is charged through the line 95, heat exchanger 97, and lines 99, into the upper portion of the fractionating tower 101. The fractionating tower is maintained under a pressure of approximately 180-220 pounds per square inch and preferably about 200 pounds per square inch. Liquid from the bottom of the fractionator is charged through line 103 to reboiler 105 where it is heated and the light fractions, such as butylene, propylene propane, and butane, together with some heavier fractions, are liberated and pass from the top of the reboiler through line 107 back to the intermediate portion of the fractionating tower 101. The unvaporized condensate, which comprises stabilized casinghead or light gasoline, is withdrawn from the bottom of the reboiler through the line 109, heat exchanger 97, cooling coil 113, and line 115, to storage.

Uncondensed gases and light vapors leave the top of the fractionating tower 101 through line

117 and pass through cooling coil 119 into reflux accumulator 121 which is maintained under substantially the same pressure as the fractionating tower 101. Any condensate which collects in the reflux accumulator is recycled from the bottom thereof through the line 123 by means of pump 125 into the top of the fractionating tower 101 to act as reflux. The uncondensed gases leave the top of the reflux accumulator 121 through the line 127 controlled by back pressure regulator 129, and may be withdrawn from the system through the line 131 controlled by valve 133, but are preferably charged through the line 135 controlled by valve 137 to admixture with the gases in the line 25. The gases withdrawn from accumulator 121 may have an olefin content of 60-75%. It will be evident that any mixture of gases desired may be fed to the polymerization system, or that gases alone from the line 135 or from the line 25 may be fed to the polymerization system. This enables the gases to be proportioned in such manner as to regulate the olefinic content of the gases charged to the polymerization unit.

The gases from lines 25 and/or 135 are charged through the line 139 into a caustic scrubber 141 where they are contacted with a caustic soda or other reagent in order to remove from the gases, hydrogen sulfide. Caustic may be charged to the caustic scrubber through line 144 and the spent reagent removed through line 142. It is desirable to remove the hydrogen sulfide because of its corrosive properties and in addition because it reacts with the olefinic hydrocarbons present in the gases to form mercaptans and other organic compounds which are deleterious to the resulting product. The desulfurized gas leaves the top of the caustic tank 141 through the line 143 and passes into a gas receiver 145, from the top of which gases are withdrawn through the line 147 and charged to the heating and reaction coil 149.

Gases may be charged to the heating and reaction coil 149 at a pressure ranging from approximately atmospheric to 175 pounds per square inch, and in passing therethrough are heated to a temperature of 1100°-1200° F., and preferably from 1125°-1175° F. The gases passing through the heating and reaction coil 149 are so proportioned that the olefinic content thereof is from 40-60% by volume of the total gas. The gas is quickly heated to the desired temperature and the latter portion of the coil serves as a soaking and reaction zone in which the temperature remains substantially constant for a period of time ranging from 5-15 seconds. The coil 149 is located in a furnace 151, heated by means of the burner 153. As shown, the coil is heated primarily by convection heat although radiant heat may be used if desired. Convection heat is preferable for the reason that radiant heat has a tendency to heat the outer surface of the tubes to an excessive degree, with the result that the gases contacting the inner surface of the tubes are heated to a much higher temperature than the gases in the middle portion thereof. Convection heat provides more even heating of the gases in the heating and reaction coil. The coil may be of any desired cross-section, but a coil of 1 1/4 inches inside diameter has been found to be satisfactory and this coil should be of sufficient length to provide a reaction time within the reaction temperature range of approximately 5-30 seconds.

The gases leave the heating and reaction coil 149 through the line 155 and may either pass through the unheated reaction zone 157 or bypass around the reaction zone 157. The reaction zone 157 may take the form of a coil of enlarged cross-sectional area, as for example, a coil of approximately 3½-4 inches inside diameter, or it may take the form of a reaction chamber. The reaction zone 157 provides additional time for reaction when necessary. However, if the coil 149 is of sufficient length to give the desired time of reaction, the zone 157 may be by-passed by passing the gases through the line 159 controlled by valve 161. A valve 163 is provided in the line 155 to enable the gases to by-pass the zone 157. After leaving the reaction coil 149 or the reaction zone 157, in the event the gases are permitted to pass therethrough, the reaction products are immediately chilled to a temperature below reaction temperature by means of direct contact with a cool hydrocarbon liquid which is injected into the reaction products passing through the line 189. The cooling liquid may be condensate formed in the process, or may be hydrocarbon oil 25 or distillate formed in a separate process. The reaction products are preferably chilled to a temperature of approximately 300°-600° F. It is important to suddenly chill the products from reaction temperature to below reaction temperature 30 in order to prevent carbon deposition which accompanies slow or gradual cooling of the reaction products. The reaction products may be further cooled to approximately atmospheric temperature by passing through the cooler 167 35 and then charged into an accumulator 169 which may be maintained at a pressure of approximately atmospheric to 25 pounds per square inch. There is a considerable pressure drop, through the heating and reaction coil, so that the pressure at the outlet of coil 149 may be approximately one half the pressure of the entering gases. Uncondensed products may leave the top of the accumulator 169 through line 171 at a temperature of approximately 100-120° F. 40 through back pressure regulator 173 and are compressed by the compressor 175 to a pressure of approximately 175-200 pounds per square inch, preferably about 180 pounds per square inch, and compressed gases pass through a preheater 177, 45 where they may be preheated to a temperature of approximately 250° F., lines 179 and 181, into the upper portion of the stabilizer 183. The condensate from the accumulator 169 is withdrawn therefrom through line 185 by means of pump 50 187 and a portion thereof may be charged through line 165 controlled by valve 191 to act as cooling fluid for the products leaving the reaction coils 149 or reaction zone 157. The remaining portion may be charged through the line 192 controlled 55 by valve 193 through heat exchanger 195, lines 197 and 181 into the upper portion of the stabilizer 183. The unvaporized liquid, which collects in the bottom of the stabilizer, is sent through the line 199 into the reboiler 201 where it is heated 60 sufficiently to drive off hydrocarbons having less than five carbon atoms. The stabilized condensate is withdrawn from the reboiler through the line 203, heat exchanger 195, line 205, cooler 207, and sent to storage. The uncondensed gases 65 leave the top of the stabilizer 183 through the line 209, pass through cooler 211 and into a reflux accumulator 213. Any condensate which collects in the accumulator 213 is returned from the bottom 70 thereof through line 215, by means of the

pump 217, into the top of the stabilizer 183 to act as reflux. The uncondensed gases leave the top of the accumulator 213 through the line 219 controlled by back pressure regulator 221 and may be either withdrawn, in whole or in part, from the system through the line 223 controlled by valve 225, but are preferably recycled to the gas receiver 145 through the line 227 controlled by valve 229. These gases may have an olefin concentration of 30-40% and are useful as a diluent 10 for gases richer in olefin concentration than that desired in the gases charged to the polymerization system.

As an example of the process carried out using the reaction zone 157, gases from the line 25, containing approximately 40% of unsaturates, and gases from the line 135, containing approximately 65% of unsaturates, were mixed so that the resulting gas had an unsaturated content of 50.4% by volume. This gas was charged to the heating and reaction coil 149 at a pressure of 149 pounds per square inch and heated therein to a temperature of 1166° F. The gases remained in the reaction section of the coil at this temperature for approximately 10 seconds and were discharged therefrom at a pressure of 73 pounds per square inch and passed into the reaction zone 157. The gases entered the reaction zone at a temperature of approximately 1150° F. and left the zone at 715° F. The time of residence in the zone 157 was approximately 35 seconds. The products leaving the reaction zone 157 were immediately chilled with condensate formed in the system to a temperature of 500° F. and the pressure dropped to 56 pounds per square inch. A total of 164,960 cu. ft. of gas was processed, of which 85,470 cu. ft. was gas from accumulator 121. No gas was recycled. A total of 184,100 cu. ft. of processed gas was obtained. A total of 7.76 barrels of condensate was obtained, of which 5.99 barrels was gasoline of 418° F. end point. A yield of 1.98 gallons of condensate and 1.52 gallons of gasoline per thousand cubic feet of fresh gas were obtained. The gas charged to the polymerization system had a specific gravity of 1.278 (air=1) and the resulting gas had a gravity of 1.102, and the unsaturated content was 35.1%. The A. P. I. gravity of the 418° F. end point gasoline was 31.8.

The 418° F. end point material was subjected 40 to Engler distillation and gave the following cuts:

	Percent off	°F.
I. B. P.		55
5		144
10		175
20		185
30		194
40		201
50		210
60		218
70		232
80		250
90		280
95		340
End point		384
Recovery	percent	417
		97.5
		65

This material was blended fifty-fifty with a motor fuel having an octane number of 41.3 and the octane number of the blend was 71.1. The octane number blending value of the product was therefore 100.9.

In this particular run practically no coke formed in the reaction coils 149 but a considerable amount of coke formed in the reaction zone 157.

The total condensate produced in this run was fractionated into a number of cuts, as follows:

§	A. P. I. gravity	Cut	Percent over	Boiling range of cut, °F.
10	34.2	Lighter than benzol	8	
	32.5	Benzol fraction	20	160-222.
	31	Toluol fraction	24	205-250.
	23.7	Xylool	9	225-325.
		Below naphthalene	9	300-400.
		Naphthalene (overcharge 66% solid and 44% liquid)	4.5	
	11.5	Blue color (unknown composition)	3	405-490.
15	10.2	Green color (unknown composition)	2	Heavier than blue cut.
		Bottoms (specific gravity 1.1)	17	
		Loss	3.5	

Another run was made in which only gas from the line 135 was fed through the polymerization system together with approximately an equal quantity of gas recycled from line 227. The run was carried out for a period of 24 hours during which time 86,310 cu. ft. of fresh gas from accumulator 121, having a specific gravity of 1.434, and 84,550 cu. ft. of recycled gas, were charged to the system, and 90,930 cu. ft. of processed gas were produced, having a specific gravity of 1.120. 8.26 barrels of condensate were produced containing 6.82 barrels of 418° F. end point material or 3.32 gallons of E. P. condensate per thousand cubic feet of fresh fractionator gas charged to the system. During this run the maximum temperature obtained in the reaction coils 149 was 1148° F. and the gases were subjected to reaction temperature for a period of about 9.8 seconds. The reaction products leaving the coils 149 were by-passed around the reaction zone 157 and chilled by means of cool condensate to a temperature of 500° F. The pressure at the inlet of the coil 149 was 149 pounds per square inch and at the outlet 73 pounds per square inch. 25 pounds per square inch was maintained on the accumulator 169 and the stabilizer was maintained under a pressure of 185 pounds per square inch. The composite gas (fresh gas plus recycle gas) charged to the polymerization unit had an unsaturate content of 48.2% and the processed gas had an unsaturate content of 37%. The condensate formed in this run had an A. P. I. gravity of 30.5 and produced a 418° F. end point material having an A. P. I. gravity of 35.8. This material, when subjected to Engler distillation, gave the following results:

55	Percent off	°F.
I. B. P.		
5	123	
10	157	
20	166	
30	179	
40	188	
50	199	
60	210	
70	225	
80	247	
90	287	
95	333	
End point	432	
Recovery	percent	98

When this end point material was blended fifty-fifty with a motor fuel having an octane rating of 41.3, it gave a blend having an octane number of 70.9. The octane number blending value of the 418° F. end point material was therefore 100.5.

During the course of this run, samples of the 75 gas feed and samples of the residual gas were

taken, and Podbielniak analyses of the gases were made, with the following results:

	Feed (including recycle)	Residual gas	5
Hydrogen			
E ₂	0.30	1.0	
CO ₂	0.30	0.32	
CH ₄	9.04	31.43	10
C ₂ H ₄	11.57	10.28	
C ₂ H ₆	14.97	17.21	
C ₃ H ₆	23.19	18.24	
C ₃ H ₈	20.25	14.36	
C ₄ H ₈	12.08	4.62	
C ₄ H ₁₀	8.17	2.92	
C ₅ +	0.45	0.72	15

It will be evident from these analyses that both the butylene and the butane take part in the reaction to a large extent, and the propane and propylene to a lesser extent.

In a third run, during a period of 24 hours, 123,010 cu. ft. of gas, comprising a mixture of fractionator gas from the line 135 and absorber gas from the line 25 were mixed in the proportion of 68.56% fractionator gas and 31.44% of absorber gas and charged to the polymerization system. The maximum temperature in the reaction coils 149 was 1154° F. and the gases were maintained at reaction temperature for a period of approximately 10.9 seconds. The gases entered the coils 149 at a pressure of 113 pounds per square inch and left at a pressure of 61 pounds per square inch. The reaction products were by-passed around zone 157 and were chilled by means of arrester fluid to a temperature of 500° F. No gas was recirculated through the line 227. 7.4 barrels of condensate were produced containing 5.87 barrels of 418° F. end point material, or a yield of 2.00 gallons of end point material per thousand cubic feet of fresh gas. The fresh gas had a specific gravity of 1.335 and contained 52.4% of unsaturates. The processed gas had an S. G. of 1.081 and contained 40.3% of unsaturates. The condensate had an A. P. I. gravity of 28.2 and yielded a 418° F. end point material having an A. P. I. gravity of 34.4. When this material was subjected to Engler distillation, it gave the following results:

	Percent off	°F.	50
I. B. P.			
5	120		
10	156		
20	167		
30	181		
40	191		
50	200		
60	212		55
70	228		
80	255		
90	298		
95	363		
Recovery	percent	98	60

This end point material was blended fifty-fifty with the 41.3 octane number motor fuel, and the resulting blend had an octane number of 71.9. The blending value of the end point material is therefore 102.5.

Material prepared in the second example was subjected to careful distillation and the boiling points plotted against the percentage distilled overhead as shown on Fig. 2. A series of plateaux may be noted occurring at the approximate boiling points 175-180°, 229-231° and 270-280° which coincide respectively with the boiling points of benzol 176°, toluol 230°, M-xytol 282°, P-xytol 280°. The horizontal length of the plateaux is 75

a measurement of the percentage of these compounds present and in this case indicates the presence of approximately 20% of benzol, 15% of toluol, and a smaller amount of xylol. The 5 large amount of toluol in the product is unusual and makes the process extremely valuable since the demand for toluol is great and for that reason its price is considerably higher than benzol.

In runs two and three practically no coke was 10 formed in the process, demonstrating that any cracking that does take place is not drastic, that is, the cracking does not result in the formation 15 of carbon and hydrogen. Mild cracking undoubtedly does occur since the volume of processed gas exceeds the volume of the gas charged. Moreover, the yields obtained on gases of different 20 gravity and the composition of the fresh and processed gases indicate that the heavier olefins, particularly butylene, take a more active part in the reaction than the lighter olefins. The run made in which the reaction zone 157 was used demonstrates the fact that gradual cooling of the 25 reaction products tends to produce coke and it therefore should be avoided. When the products were taken directly from the reaction coils 149 and quickly chilled before any substantial drop 30 in temperature occurs, practically no coke is formed. Not only does formation of carbon occur during this period of gradual cooling but heavy 35 tarry materials are formed at the expense of the more desirable benzol, toluol, and xylol fractions.

When the percentage of unsaturates in the 35 fresh charging stock substantially exceeds 60%, the carbon to hydrogen ratio is so high that the 40 dehydrogenation of part of the charge to form aromatic compounds such as benzol and toluol, is accompanied by deposition of carbon. Such a condition is to be avoided in that it renders the process less economic in having to provide 45 for the removal of solid carbon deposits in the reaction zones.

With fresh charging stocks having more than 60% of olefins, the process may be operated at 50 reaction temperatures of from 1075°-1150° F., preferably 1100°-1125° F., without carbon deposition. Under these conditions a smaller proportion of 55 the liquid products will be dehydrogenated to aromatic compounds and a larger proportion will be olefins and naphthenes which are of lower commercial value.

The formation of toluol cannot be promoted at 60 temperatures substantially below 1100° F. Below substantially 40% of unsaturates the reaction will proceed at the 1125°-1175° F. temperature 65 range set forth above, but the yield of total liquid products will be relatively low although the percentage of benzol and toluol in the liquid product will be as great as found in the product from gases containing percentages of olefins in the preferred range. An increase in reaction temperature will not increase the liquid yield, but will result in excessive dehydrogenation of part of the charge and will be accompanied by carbon deposition.

It is essential that the pressure remain relatively low since high pressures tend to suppress an increase in the total volume or a decrease in the average molecular weight of the components of the system undergoing reaction. It is necessary that bodies of low molecular weight and of low carbon to hydrogen ratio such as methane and hydrogen should be allowed to form in order that another portion of the charge may be allowed to form toluol and benzol of high carbon to hydrogen ratio.

At high pressures the reaction is chiefly polymerization instead of dehydrogenation accompanied by polymerization, thereby making the reaction difficult to control, owing to evolution of heat of polymerization in the early stages, and furthermore, at the high temperatures necessary to produce toluol, decomposition of the products of prior polymerization result in carbon deposition. The inlet pressures to the reaction coil should not exceed 150-250 pounds per square 10 inch.

It will be seen that not only has a process been provided for preparing high octane number motor fuels under conditions of temperature and pressure considerably below those heretofore used, 15 but the process provides a means for producing large quantities of toluol and other higher boiling aromatic hydrocarbons.

What I claim is:

1. The process of converting olefin containing 20 gases to liquid hydrocarbons containing a large proportion of aromatics boiling above the boiling point of benzol which comprises separating the gas into a fraction containing in excess of 60% 25 olefins and a fraction containing less than 60% olefins, mixing sufficient low olefin content gas with the high olefin fraction to bring the olefin content thereof within the range of 40 to 60%, heating the mixed gas in the substantial absence 30 of non-hydrocarbon gas to a temperature between 1125° and 1175° F. under pressures between atmospheric and 250 pounds per square inch, maintaining the gas within the aforesaid temperature range for a period of 5 to 30 seconds, 35 cooling the resulting products and separating the gases from the resulting liquids.

2. Process in accordance with claim 1 which is carried out in the substantial absence of catalysts.

3. Process in accordance with claim 1 in which 40 a portion of the fraction containing less than 60% olefins is mixed with the high olefin fraction to bring the olefin content thereof within the range of 40 to 60%.

4. Process in accordance with claim 1 in which 45 a portion of the reaction gas is mixed with the high olefin fraction to bring the olefin content thereof within the range of 40 to 60%.

5. Process in accordance with claim 1 in which 50 a portion of the gas fraction having an olefin content below 60% and a portion of the reaction gas are mixed with the high olefin fraction in order to bring the olefin content thereof within the range of 40 to 60%.

6. The process of converting hydrocarbon gases 55 containing approximately 40% to 60% of olefins into liquid hydrocarbons rich in toluol which comprises subjecting said gases in the substantial absence of non-hydrocarbon gas to temperatures within the limits of approximately 1125° F. to 60 1175° F. and under super-atmospheric pressure below that at which carbon formation is actively promoted for a period of time ranging from 5 to 30 seconds, cooling the reaction products below reaction temperature and separating the liquid 65 from the gaseous reaction products.

7. Process in accordance with claim 6 in which the olefins are chiefly butylenes.

8. Process in accordance with claim 6 in which the pressure is not in excess of approximately 70 250 pounds per square inch.

9. Process in accordance with claim 6 conducted in the absence of a catalyst.

10. The process of converting hydrocarbon gases containing approximately 40% to 60% of 75

olenfins into liquid hydrocarbons rich in toluol which comprises subjecting said gases in the substantial absence of catalysts and of non-hydrocarbons to temperatures of approximately 1125° to 1175° F. under super-atmospheric pressure below that at which carbon formation is actively promoted for a period of time ranging from 5 to

30 seconds, cooling the reaction products below reaction temperature and separating the liquid from the gaseous reaction products.

11. Process in accordance with claim 10 in which the pressure is not substantially above 250. 5 pounds per square inch.

CARY R. WAGNER.
